 HIGH-CARBON PRECIPITATION-HARDENING
AUSTENITIC STEEL ALLOY

Horace Pops, Wilkinsburg Borough, Pa., assignor to
United States Steel Corporation, a corporation of Dela-
ware
No Drawing. Filed Oct. 1, 1964, Ser. No. 400,907
4 Claims. (Cl. 148—38)

This invention relates to high-carbon precipitation-harden-
ing austenitic iron alloys characterized by high tem-
perature tensile strength suitable for aircraft and missile
uses.

Aircraft and missile structures require alloys that will
retain strength in the range of 1000 to 1500 F. Presently used materials generally are low-carbon, chromium,
nickel, iron alloys containing titanium as a major harden-
ing agent together with molybdenum, vanadium and alu-
minum. Strengthening of these alloys is accomplished by
precipitation or age-hardening and is usually attributed to
internal lattice strains produced by the precipitation of
intermetallic compounds such as Ni₃(TiAl). At high
temperatures the precipitates agglomerate to larger par-
ticles and thus lose their effectiveness. The carbon con-
tent of titanium-bearing high-temperature alloys is kept
at a minimum since with increased carbon contents, the
titanium acts as a carbide stabilizer and forms relatively
stable titanium carbide dispersoids so that the matrix is
depleted of titanium and is therefore not available as a
precipitation-hardening element. High-carbon, high-tem-
perature iron alloys are also known; these are usually
strengthened by the precipitation of chromium carbides
and are used mainly for valves and the like. However
such steels have inferior mechanical properties at the
higher temperatures associated with aircraft and missile
applications.

It is an object of this invention to provide an austenitic
iron alloy having a considerably higher level of strength

2

for high temperature service because the zirconium carbide
particles, which form, become agglomerated and
segregate in the as-cast ingots. On the other hand, I have
discovered that with relatively high amounts of carbon
and zirconium, a large number of uniformly dispersed
zirconium carbide dispersoids are formed and conse-
quently no internal stress raisers are produced because
of the uniform distribution. In addition to this disper-
sion strengthening mechanism, one or more phases pre-
cipitate out of the matrix during aging heat treatments
thereby extending the high strength characteristic of the
steel over longer periods at elevated temperature. Thus
the mechanical properties of the alloy of this invention are
believed to be obtained by a superimposition of multiple
strengthening mechanisms. Moreover despite the large
volume fraction of carbide particles, the alloy of this
invention can be readily hot or cold swaged or machined.

The austenitic iron alloy of my invention has the fol-
lowing compositional range by weight percent:

20	Carbon	-----	.51 to .60
	Chromium	-----	10 to 20
	Nickel	-----	15 to 25
	Zirconium	-----	2.0 to 4.0
	Titanium	-----	2.0 to 4.0
25	Molybdenum	-----	2.0 to 4.0
	Tungsten	-----	2.0 to 4.0
	Cobalt	-----	2.0 to 4.0
	Boron	-----	Up to .008

30 balance substantially iron and incidental residuals or im-
purities. In the latter regard, residuals and impurities
include not only the normal small amounts of phospho-
rus, sulphur and dissolved gases present in steels but also
manganese, silicon and aluminum commonly present as
35 the results of manufacturing processes; the latter elements
being unnecessary to the properties of the present alloy
but not deleterious thereto in amounts up to 1.0% each.

The following heats of steel will illustrate the invention:

TABLE I

Steel	Zr	Ti	C	Mo	W	B	Co	Cr	Ni	Fe
1-----	2	4	0.8	2	2	0.008	4	15	20	Bal.
2-----	2.88	2.81	0.68	2.92	3.1	0.0042	2.98	15	20	Bal.
3-----	2.98	3.30	0.57	2.95	3.11	0.004	2.92	15	20	Bal.
4-----	2.99	3.3	0.56	2.93	2.98	0.000	2.96	15	20	Bal.

and improved ductility at temperatures above about 1200°
F. than available heretofore.

A further object of this invention is to provide a steel
having a matrix that is strengthenable by dispersion of
relatively stable carbide particles as well as by precipita-
tion hardening.

I have discovered that the foregoing objects can be ob-
tained in an austenitic chromium nickel steel containing
high carbon within a restricted range together with limited
amounts of zirconium, titanium, molybdenum, tungsten
and cobalt; further that the inclusion of a small amount
of boron in the composition is very beneficial. Small
additions of zirconium are not customary in iron alloys

55 The tensile strength at various test temperatures of
the foregoing steels after precipitation hardening is listed
in the following Table II along with that of A-286 steel
which is sometimes used for high temperature service.
A-286 is a commercially available steel of the low car-
bon, chromium, nickel, titanium and iron type. As ap-
parent upon comparison of the properties of steels 4 and
A-286, the present invention affords materials of con-
siderably higher strength at elevated temperature than
available heretofore. The ultimate strength of steel 4 is
65 about 55% greater at 1500° F. than that of A-286 while
its yield strength at this temperature is about 160%
greater. Moreover steel 3 which is essentially the same

as steel 4, except for the presence of 0.004% boron affords an even more remarkable result showing improvements in both tensile and yield strengths of better than 45% at 1300° F. and of more than 100% at 1500° F. As is indicated by comparing the elongations of steels 3 and 4, boron markedly increases the elevated temperature strength of the alloys without lowering the ductility. The effects of boron however are lost when the carbon content of the alloys is increased, see steel 1. That the carbon content must be closely controlled is further evident from steels 2 and 3, wherein a relatively small increase from .57 to .68% has resulted in a large drop in the tensile strength.

In general and as evident from Table III, solution annealing at temperatures toward the lower end of the range 50 1800 to 2200° F. will produce somewhat higher levels of strength. Annealing time is preferably held to the minimum needed to achieve substantially uniform temperature throughout the alloy. While this will vary with thickness of section, a half hour at temperature is in most instances sufficient.

As also evident from Table III, considerably longer times are involved in the precipitation treatment; aging for 60 100 hours or more at 1300° F. being required to develop maximum strength. However it will be noted that the increase in strength with times longer than 10 hours is minor; consequently treatment for longer than about 10 hours are uneconomical and may even be detrimental.

The effect of aging temperature at a constant treating time of 10 hours is illustrated in Table IV. It will be noted 65 that the optimum aging temperature rises to about 1400° F. as the temperature used in the solution anneal is increased. More important however is the fact that the highest strength level is achieved by solution annealing at about 1850° F., in combination with aging at about 70 1300° F. It is apparent that lower aging temperatures, e.g. 1200° F., are usable but would require extension of the time of treatment, while higher aging temperature, e.g. 1500° F. should be avoided since the strength level drops even when the treating time is drastically shortened. The latter is illustrated by the data of Table V.

The composition of the A-286 steel included in the foregoing table had the following composition:

C	0.045
Mn	1.35
Si	.95
P	.02
S	.02
Cr	15.5
Ni	26.0
Mo	1.25
Ti	1.95
V	.3
Al	.20

The properties of the alloys of the present invention are developed by heating treatment involving a solution anneal at temperature ranging from about 1800 to 2200° F. followed by a precipitation or aging treatment at a lower temperature.

The effects of variations in treating conditions are illustrated by the data of Tables III, IV and V. While the tabulated data are specific to steel 3 when tested at 1300° F., they may be considered typical of all the compositions of the present invention as regards the variation in properties to be expected with variations in temperature of solution anneal and the time and temperature used in the precipitation treatment.

TABLE V.—EFFECT OF TIME AND TEMPERATURE OF AGING ON MECHANICAL PROPERTIES OF STEEL 3 AS DETERMINED BY TENSILE TESTS AT 1,800° F.

Solution Treatment		Aging Treatment		Tensile Strength (p.s.i.)	Yield Strength (p.s.i.)	Average Elong. in 1", percent	5
Temp. (° F.)	Time (hrs.)	Temp. (° F.)	Time (hrs.)				
1,850	1/2	1,300	1	120,300	93,800	10.8	
1,850	1/2	1,300	10	131,300	109,700	9.4	
1,850	1/2	1,500	1	103,700	87,500	19.8	
1,850	1/2	1,500	10	95,000	69,400	14.5	
2,150	1/2	1,300	1	89,600	53,800	12.1	
2,150	1/2	1,300	10	106,100	83,300	11.7	
2,150	1/2	1,500	1	100,100	87,600	14.8	
2,150	1/2	1,500	10	90,500	61,700	11.8	

In summary, optimum practices of the invention involve a short time solution anneal of the alloys disclosed at about 1850° F. followed by precipitation hardening by heating to about 1300° F. (1275–1350° F.) for about 10 hours.

When thus treated, the high-carbon precipitation-hardening austenitic steels of this invention are characterized by maintenance of high strength for more than 1000 hours at temperatures above 1200° F. and up to about 1500° F., a significant improvement over the presently available steels used for high temperature service.

While I have shown and described several specific embodiments of my invention, it will be understood that these embodiments are merely for the purpose of illustration and description and that various other forms may be devised within the scope of my invention, as defined in the appended claims.

I claim:

1. A precipitation-hardening austenitic iron alloy consisting essentially of, by weight percent

Carbon	0.51 to 0.60
Chromium	10.0 to 20.0
Nickel	15.0 to 25.0
Zirconium	2.0 to 4.0
Titanium	2.0 to 4.0
Molybdenum	2.0 to 4.0
Tungsten	2.0 to 4.0
Cobalt	2.0 to 4.0

with the balance iron and incidental residuals.

2. A precipitation-hardening austenitic iron alloy consisting essentially of, by weight percent

Carbon	0.51 to 0.60
Chromium	10.0 to 20.0
Nickel	15.0 to 25.0
Zirconium	2.0 to 4.0
Titanium	2.0 to 4.0
Molybdenum	2.0 to 4.0
Tungsten	2.0 to 4.0
Cobalt	2.0 to 4.0
Boron	Up to .008

10 with the balance iron and incidental residuals.

3. A precipitation-hardened austenitic iron alloy consisting essentially of, by weight percent

Carbon	0.51 to 0.60
Chromium	10.0 to 20.0
Nickel	15.0 to 25.0
Zirconium	2.0 to 4.0
Titanium	2.0 to 4.0
Molybdenum	2.0 to 4.0
Tungsten	2.0 to 4.0
Cobalt	2.0 to 4.0

with the balance iron and incidental residuals.

4. A precipitation-hardened austenitic iron alloy consisting essentially of, by weight percent

Carbon	0.51 to 0.60
Chromium	10.0 to 20.0
Nickel	15.0 to 25.0
Zirconium	2.0 to 4.0
Titanium	2.0 to 4.0
Molybdenum	2.0 to 4.0
Tungsten	2.0 to 4.0
Cobalt	2.0 to 4.0
Boron	Up to .008

with the balance iron and incidental residuals.
